UNITED STATES PATENT OFFICE.

CLINTON DE WITT WAGNER, OF CEDAR RAPIDS, IOWA.

PIPE-DAMPER.

1,101,222.

Specification of Letters Patent. Patented June 23, 1914.

Application filed April 17, 1914. Serial No. 832,662.

To all whom it may concern:

Be it known that I, CLINTON DE WITT WAGNER, a citizen of the United States, residing at Cedar Rapids, in the county of 5 Linn and State of Iowa, have invented certain new and useful Improvements in Pipe-Dampers, and do hereby declare the following to be a full, clear, and exact description of the invention, such as will enable others 10 skilled in the art to which it appertains to make and use the same.

This invention relates to pipe-dampers, and more particularly to those of large size used in connection with hot-air furnaces; and the 15 object of the invention is to provide a handle and spur or spindle which are inexpensive, easily attached to the damper disk, and when so attached the damper may be easily inserted in a joint of pipe.

20 The invention is fully disclosed in the description and claims following, reference being had to the accompanying drawing, in which—

Figure 1 is a plan view illustrating my 25 improved damper, partly in section. Fig. 2 is a view of the same as seen from the right end of Fig. 1. Fig. 3 is a side view of the handle, partly in section. Fig. 4 is a view in perspective of the spur or spindle. Fig. 30 5 is a view of the outer washer to be mounted on the handle. Fig. 6 is a similar view of the inner washer.

Referring to the drawing, 1 denotes a hot-air or smoke pipe, perforated at 2 and 3 to 35 receive the handle and spur, respectively of a damper. The latter, in the case of furnaces, is usually a round disk of sheet metal 4, cut out by the tinsmith. The attachments for mounting and turning the damper form 40 the subject matter of this invention, taken in connection with so forming the disk as to adapt it for its attachments. One side of the disk is provided with a spur 5, which serves as one of the pivots on which the 45 damper turns in the pipe. This is formed of wire, bent to the helical form shown at 6, so as to make a broad bearing on one side of the disk. One end of the wire projects outwardly at 7, and the other end is bent 50 down at a right angle or less at 8, and cut diagonally at 9 and at the outer side as regards the bend. The object of this diagonal cut is to make a sharp point at the end of the tang which will admit of the tang being 55 driven through the disk without preliminary punching, the plate being placed over a soft wood block, a hole, or the slightly opened jaws of a vise. The inclination of the cut is such, also, that when so driven through the plate the tang may be clenched 60 on an iron block without turning over the plate. It is to be noted furthermore that the fastening is by a single tang, and at some distance from the edge of the plate. If, as often happens, the workman is not 65 careful to center the spur exactly, or what is still more likely to occur, fails to punch the holes in the pipe exactly central, the spur may be turned to one side or the other, as indicated in Fig. 1, and the eccentricity does 70 not cause the damper to bind on the inside of the pipe. The other pivot for the damper is also formed of wire, and it and its connections will now be described. A piece of stout wire 10 is bent back on itself at 11, 75 and twisted to form a shank 12, the shank and that portion of the loop leading to it being of smaller diameter than the extreme terminal of the loop. The free legs 13 and 14 are provided with oppositely projecting 80 terminal tangs 15, bent at a right angle or less, and cut diagonally at 16 in the same manner and for the same purpose as is the tang of the spur. The legs pass through holes 17 in a cupped washer 18, and are then 85 bent outwardly to about a right angle, as shown. The bending of the legs forces the washer tightly into the twist of the shank, thus holding it firmly in position. It is 90 cupped on the side next the shank so that the bur 19 formed on the inner side of the pipe by punching the hole for the shank does not interfere with the washer or any other part of the damper, and the edge of the washer on the concave side makes a neat 95 and firm bearing against the inside of the pipe. To make a place for the cupped washer a notch 20 is cut in that side of the damper. The shank is attached to the 100 damper by driving its tangs through the plate from opposite sides, and clenching them, substantially as shown. Adjacent to the cupped washer is another washer 21, preferably beaded at 22 to form an inner seat for a spring 23 slipped over the shank. 105 To the end of the shank is attached a button or handle 24 provided with a substantially diamond-shaped hole 25, the shorter axis of which is less than the diameter of the shank-loop at its extremity. The longer 110 axis of the hole permits the handle to be slipped on the shank, pressing the interposed

spring inwardly, and then by a quarter turn it is brought to holding position on the shank, the spring then serving to force the handle into this holding position, and also 5 to force the outer washer to bearing position against the outside of the pipe. The opposed washers thus afford a broad, smooth bearing on the inside and outside of the pipe, and the spring supplies the necessary 10 friction to hold the damper in any desired position.

Having thus described my invention, I claim:

1. The combination with a damper-plate, 15 of a spur formed of wire, the head portion thereof being helical, and terminating in a centrally disposed tang bent substantially at right angles to the plane of the helix, and beveled on its outer side at the end.

2. As a new article of manufacture, a 20 pipe-damper spur formed of wire, and having a helical head portion terminating in a centrally disposed tang bent at practically a right angle to the plane of the helix, and sharpened on its outer side at the end.

3. In combination with a damper-plate, 25 a handle, comprising a shank formed of a piece of wire bent back upon itself and twisted a part of its length to form the shank proper, the diverging legs being provided with sharpened tangs adapted to penetrate and clench against the plate, and the 30 terminal loop being widest at its extremity, and a handle adapted to slip over said loop and engage it by turning partly around and 35 forcing it outwardly.

4. In combination with a damper-plate, 40 a handle composed of a piece of wire folded upon itself and twisted for some distance to form a shank, the loop being widest at its extremity, and the diverging legs being provided with sharpened tangs adapted to penetrate the plate and clench thereon, a handle adapted to slip over the loop and en-

gage the same when turned, and a spring 45 mounted on the shank and adapted to press the handle outwardly into engagement with said loop.

5. In combination with a damper-plate, 50 a handle composed of a piece of wire folded back upon itself forming a loop widest at its extremity; the doubled wires twisted to form a shank, and the diverging legs being provided with sharpened tangs adapted to penetrate said plate, a handle adapted 55 to slip over said loop and engage the same when turned, a washer adapted to bear against the outside of the pipe, and a spring interposed between the handle and washer.

6. In combination with a damper-plate, 60 a shank attachable thereto, having an outward extension largest at its end, a handle adapted to slip over said end and engage it when turned on the shank, a spring adapted 65 to hold said handle in engagement, and an internal, cupped washer adapted to bear against the inside of the pipe outside the bur formed by punching the same.

7. In combination with a damper-plate, 70 a spur pivotally connected with said plate, and a handle comprising a shank with diverging legs having terminal tangs adapted to penetrate the plate, a handle or button attachable to the shank by slipping over 75 its end and turning it a little on said shank, a spring adapted to hold the button in engagement, a washer engaged by the inner end of the spring, and a cupped washer opposed thereto, and adapted to bear on the inner side of the pipe, said plate being 80 notched to receive said cupped washer.

In testimony whereof I affix my signature in presence of two witnesses.

CLINTON DE WITT WAGNER.
